US00D801372S

(12) **United States Design Patent** (10) Patent No.: **US D801,372 S**
(45) Date of Patent: **** Oct. 31, 2017**

(54) **DISPLAY SCREEN WITH GRAPHICAL USER INTERFACE**

(71) Applicant: **MITSUBISHI ELECTRIC CORPORATION**, Tokyo (JP)

(72) Inventors: **Hirohiko Higuchi**, Tokyo (JP); **Tomohiro Yatagawa**, Tokyo (JP); **Nobuhiko Ina**, Tokyo (JP)

(73) Assignee: **MITSUBISHI ELECTRIC CORPORATION**, Tokyo (JP)

(**) Term: **15 Years**

(21) Appl. No.: **29/592,105**

(22) Filed: **Jan. 26, 2017**

Related U.S. Application Data

(62) Division of application No. 29/546,329, filed on Nov. 20, 2015, now Pat. No. Des. 786,910.

CLAIM

The ornamental design for a display screen with graphical user interface, as shown and described.

DESCRIPTION

The FIGURE is a front view of an image screen of a display screen with graphical user interface showing our new design.

The outermost broken lines illustrate a display screen and form no part of the claimed design. The remaining broken lines illustrate portions of the graphical user interface that form no part of the claimed design.
